UNITED STATES PATENT OFFICE.

GUY E. DICK AND ROBERT M. BIGLER, OF CHIPPEWA FALLS, WISCONSIN.

EXPLOSIVE-ENGINE.

1,126,723.

Specification of Letters Patent.

Patented Feb. 2, 1915.

Application filed June 9, 1913. Serial No. 772,636.

To all whom it may concern:

Be it known that we, GUY E. DICK and ROBERT M. BIGLER, citizens of the United States, residing at Chippewa Falls, in the 5 county of Chippewa, State of Wisconsin, have invented a new and useful Explosive-Engine, of which the following is a specification.

The present invention relates to improvements in explosive engines, one object of the 10 invention, being the provision of a valve structure in which the valve is so mounted as to dispense with the use of packing rings or other packing medium, the valve itself 15 being a resilient normally expanding member, and mounted for oscillation, so that the same is properly operated to control the intake and exhaust of the engine.

A further object of the present invention, 20 is the provision of a novel valve structure, the valve itself being composed of a split cylinder having a normal tendency to separate, said cylinder being insertible within a casing disposed adjacent the respective intake and exhaust ports of the engine, such 25 take and exhaust ports being led into the head of the engine so as to reduce the compression and explosion space, thereby utilizing to the maximum, the power generated by 30 the explosion of the compressed charge.

With the foregoing and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed without departing 40 from the spirit of the invention.

In the drawings Figure 1 is a transverse sectional view through the cylinder showing the valves in operable relation, the operating mechanism being shown in diagram. 45 Fig. 2 is a side elevation of one cylinder of an engine showing the valve casing and manifold connection. Fig. 3 is an enlarged perspective view of one of the intake or exhaust valves *per se*.

50 Referring to the drawings, the numeral 1 designates the cylinder of the engine, which is provided with the explosion chamber 2, having the intake port 3 and the exhaust port 4, said ports being so disposed as 55 to be in direct communication with the chamber and thus prevent any pocketing or

dead space, and so trapping the explosive charge, as to cause the exertion of the maximum explosion power thereof upon the piston 18.

Two horizontally disposed cylindrical valve casings 5 and 6 are provided, each one being adjacent to its respective ports 3 and 4 and in communication therewith, and having formed through the outer wall the apertures 7 and 8 respectively, the purpose of which will presently appear. A water jacket 9 surrounds the cylinder 1 and also the valve casings 5 and 6, so that all parts of the engine subjected to friction and heat 70 will be properly cooled.

The valves 10 and 10', each one of which is constructed similarly, are mounted for oscillation in the respective casing 5 or 6, and as the construction of each valve is similar, 75 the description of one will suffice for both. The valve 10, as clearly shown in Fig. 3, is composed of a cylinder, a portion at 11 of which is thicker than the diametrically opposed portion at 12, there being provided a 80 longitudinal slot or port 13, which constitutes the port for alignment with the respective intake or exhaust port of the engine. The middle of the valve is so constructed and tensioned as to have a normal tension to 85 expand and increase the size of the port 13, and consequently resiliently engage the adjacent wall of its casing 5 or 6, and thus provide a tight fit to prevent the escape of gases due to the compression and exhaust stroke 90 of the piston 18. These valves are disposed for oscillation in their casings 5 and 6, and each valve is provided with an arm 11'; which projects through its respective slot or aperture 7—8, by means of which the same 95 is readily accessible as before stated for operation.

In order to properly operate the respective valves 10—10' in proper timed relation to admit of the introduction of the explosive 100 charge within the chamber 2 and the exhaust of the burnt gases therefrom, the reciprocatory rods 14—14' are connected to the respective arms 11 of the two valves as clearly shown in Fig. 1, the lower ends being 105 disposed upon the eccentrics 15—15' carried by the counter shafts 16—16' of the engine. Each counter shaft is operably connected to the crank shaft 17 and thus the power piston 18 will operate the counter 110 shafts and in proper timed relation for the respective valves 10—10'. In the present in-

stance, the valves are constructed and arranged to provide a four-cycle engine, but it is apparent that the same may be so constructed and arranged as to produce a two cycle engine. The rods 14—14' and eccentrics 15—15' are indicative of one of many means whereby the valves 10—10' may be operated.

What is claimed is:

- 10 An explosive engine, including a power cylinder having oppositely disposed intake and exhaust ports adjacent the hood thereof, two parallel horizontally disposed cylindrical valve casings carried by the cylinder, one to each port, each casing being open at one end, two longitudinally split normally expanding open ended crescent in cross section shaped valves, one to each casing insertible
- 15

through the open end of the casing, a power piston, a crank shaft, means operably connecting the crank shaft to the valves, whereby the valves are oscillated to cause the slits thereof to be placed into and out of registration with the respective ports of the cylinder, the normal tension to expand of the valves packing the same and preventing leakage within the casing.

In testimony that we claim the foregoing as our own, we have hereto affixed our signatures in the presence of two witnesses.

GUY E. DICK.
ROBERT M. BIGLER.
